UNITED STATES PATENT OFFICE.

HENRY F. MANN, OF PITTSBURG, PENNSYLVANIA.

IMPLEMENT FOR CAPPING AND UNCAPPING CARTRIDGE-SHELLS.

SPECIFICATION forming part of Letters Patent No. 288,950, dated November 20, 1883.

Application filed June 26, 1883. (Model.)

To all whom it may concern:

Be it known that I, HENRY F. MANN, a citizen of the United States, residing at Pittsburgh, in the county of Allegheny and State of Pennsylvania, have invented certain new and useful Improvements in Devices for Capping and Removing Caps from Cartridge-Shells; and I hereby declare the following to be a full, clear, and exact description of the same, reference being had to the accompanying drawings, in which—

Figure 1 is a sectional view showing in full line the devices in position for capping a shell, and in dotted line the position for decapping a shell. Fig. 2 is a detached sectional view of the cartridge-post and detachable sleeves for adapting the same to cartridges of different caliber. Fig. 3 shows a modified manner of actuating the plunger.

Like letters refer to like parts wherever they occur.

My invention relates to that class of devices employed in removing the old caps from cartridge-shells and in applying fresh caps thereto, whereby the old cap can be removed and the new cap applied to the shell continuously and without a transfer or second handling of the shell; and it has for its object to simplify the instrument by reducing the number of parts, and so combining the same as to obtain accuracy and facility of operation with durability and reduction of the cost of manufacture.

I will now proceed to describe my invention more specifically, so that others skilled in the art to which it appertains may apply the same.

In the drawings, *a* indicates a suitable base-plate, to which is secured a shell-post, *b*, having a central bore for the reception of a plunger, *c*. The post is preferably tapered slightly at the top, as at *b'*, which facilitates the placing of the shell in position and accommodates any variations in shape in the base of the shell. The diameter of this post is usually made to correspond with a shell of the smallest gage or caliber in demand, and, in order to adapt it to the larger gages or calibers, detachable sleeves *e* are provided. If, for instance, it is desired to adapt the post to use with but two different gages—say 16 and 10—the post would be made for a 16 diameter, and the bore of the sleeve *e* would be such as to adapt it to receive the shell-post *b*, while its outer diameter would correspond with a No. 10 gage or

caliber cartridge-shell; and so any two or more given gages may be used by making the post one diameter, and a series of sleeves having internal diameters to fit the post and external diameters of the desired gage—as, for instance, 8, 10, 12, &c. In some cases it may be desirable to increase the number of changes which can be made, in which case a nest of sleeves, *e' e''*, &c., may be employed, (see Fig. 2,) the outer diameter of each sleeve corresponding to a given caliber shell, while its interior diameter or bore corresponds with the next smaller of the series over which it fits. The sleeve *e*, or series of nests of sleeves, should be so secured to the shell-post *b* that they will not be displaced when withdrawing a cartridge-shell, and for this purpose the sleeve may be slotted below, so as to permit it to be contracted by a screw passing through lugs on the sides of the slot. A set-screw may be used, a bayonet-lock, (as shown in the drawings,) or any other well-known means. The bayonet-lock will serve very well where a nest of sleeves is used. The base of the shell-post *b* is slotted to permit the passage of one arm of a bent lever, *d*, to which the central plunger, *c*, is pivoted, and by which it is actuated. By pivoting or linking the central plunger to its actuating-lever the plunger is projected and withdrawn with certainty, and the use of springs is avoided.

d indicates a bent or elbow lever for actuating the central plunger, *c*. This lever *d* has a vertical arm, which rises to substantially the height of the shell-post, and has pivoted to its upper end the capping and decapping lever, *f*, and has also a horizontal arm, to which the central plunger, *c*, is pivoted.

There are several ways in which the parts may be arranged and connected at the will of the constructor—as, for instance, the fulcrum-pivot of the lever *d* may be at or near the angle, and its connection with the plunger *c* near the end of the horizontal arm, as shown in full line, or the lever *d* may have its fulcrum at or near the extremity of the short arm, and its connection with the plunger *c*, near the middle of the short arm, as shown in Fig. 3, either of which or equivalent mechanical means may be adopted for actuating said plunger. *d'* indicates spurs or stops for limiting the movement of lever *d*, and consequently the movement of plunger *c*.

f indicates the capping and decapping le-

ver. This lever is pivoted on the free arm of the elbow-lever *d*, so that the elbow-lever can be actuated by the capping and decapping lever. Upon the lever *f*, back of the pivot-point, are two projections, one, *g*, for capping, the other, *h*, for uncapping, the shell. The distance of the first from the pivot-point (or fulcrum) of lever *f* is such that it stands over the center of the shell-post *b* when the lever *d* has been drawn to the extent of its movement in one direction or toward the shell-post *b*, while the distance from the pivot to the second is such as will bring it over the center of the shell-post when the lever *d* has been pushed in the opposite direction or away from the post. The projection *g*, which is used in applying a cap, is simply a nipple or projection with a flat face, while the one *h*, which is used in uncapping the shell, is a slotted lug or any low-faced projection or projections which will straddle the cap and bear directly on the base of the cartridge-shell. When the lever *d* has its fulcrum arranged as shown in full line, Fig. 1, the capping-lug will be next to the pivot as the plunger *c* will be withdrawn when the lever is drawn forward; but if the fulcrum is at the extremity of short arm of lever *d* (see Fig. 3) then the decapper *h* will be located next to the pivot-point of lever *f*, as the plunger *c* will be projected when the lever *d* is drawn toward the shell-post *b*. If there is a tendency in the fulcrum-point of lever *f* to change when the lever *d*, upon which it is pivoted, is at the greatest distance from the shell-post, it may be prevented by forming a swell or shoulder, *i*, upon the outer side of the projection next to the pivot-point, and as this strikes the edge of the cartridge-shell and rides down on the same it will arrest the slipping of the lever, so that projection *h* will descend over the center of the shell-post *b*.

The construction of the devices being substantially as hereinbefore specified, will operate as follows: The shell is slipped upon the post and if capped the lever *f* is moved so as to bring the decapper *h* over the center of the shell-post *b*, which movement of the lever *f* operates the bent lever *d*, which in turn actuates the central plunger, *c*, causing it to project through the top of the shell-post against the cap and carries up with it the cartridge-shell *t*. The lever *f* is then forced down, causing the decapper *h* to straddle the cap, bear upon the cartridge-shell, forcing the same down upon the top of the post and lifting the cap out of the recess of the shell. The lever *f* is then moved, so as bring the capper *g* over the center of shell-post *b*, which movement actuates lever *d* in reverse direction and withdraws the central plunger, *c*. A fresh cap is now placed over the cap-seat, and the descent of the lever causes the projection or capper *g* to force it down into the cap-seat, after which the shell is removed from the post *b*.

65 The main advantages of my invention are that a single set of devices is obtained which

is adapted for both capping and decapping cartridge-shells, and said operations can be consecutive without removing the shell from the post; or the devices can be used for continuously capping or continuously decapping, at the will of the user; and that such devices are simple, easily operated, compact, and not liable to get out of order.

Having thus described my invention, what I claim, and desire to secure by Letters Patent, is—

1. In a device for capping and decapping cartridge-shells, the combination of a fixed hollow shell-post, an axially-movable plunger arranged therein, an elbow-lever pivoted at its lower end on the bed of the fixed shell-post and connected to the movable plunger, and a capping and decapping lever pivoted on the elbow-lever, substantially as and for the purposes specified.

2. In a device for capping and decapping cartridge-shells, the combination of a fixed hollow shell-post, an axially-movable plunger arranged therein, an elbow-lever connected with the axial-plunger, pivoted at its lower end on the bed of the shell-post, and provided with spurs to limit the motion of the elbow-lever and axial plunger, substantially as and for the purposes specified.

3. In a device for capping and decapping cartridge-shells, the combination of a fixed hollow shell-post, an axially-movable plunger arranged therein, an elbow-lever connected with the axial plunger and pivoted at its lower end on the bed of the shell-post, a lever pivoted on the free arm of the elbow-lever and provided with capping and decapping lugs, substantially as and for the purposes specified.

4. In a device for capping and decapping cartridge-shells, the combination of a fixed hollow shell-post, an axially-movable plunger arranged therein, an elbow-lever connected with the axial plunger and pivoted at its lower end on the bed of the shell-post, a lever pivoted on the free arm of the elbow-lever and provided with capping, decapping, and an intermediate guide-lug, substantially as and for the purposes specified.

5. In a device for capping and decapping cartridge-shells, a shell-post provided with a detachable sleeve for changing the post to suit shells of different caliber, substantially as specified.

6. In a device for capping and decapping cartridge-shells, the combination, with a shell-post, of a nest of detachable sleeves for adjusting the post to shells of different caliber, substantially as specified.

In testimony whereof I affix my signature, in presence of two witnesses, this 23d day of June, 1883.

HENRY F. MANN.
